T. W. KINGS.
FUEL PUMP.
FILED JUNE 9, 1919.

UNITED STATES PATENT OFFICE.

THOMAS WILLIAM KINGS, OF CHICAGO, ILLINOIS, ASSIGNOR TO INTERNATIONAL HARVESTER COMPANY, A CORPORATION OF NEW JERSEY.

FUEL PUMP.

Application filed June 9, 1919. Serial No. 302,847.

To all whom it may concern:

Be it known that I, THOMAS W. KINGS, a subject of King of Great Britain, residing at Chicago, in the county of Cook and State 5 of Illinois, have invented certain new and useful Improvements in Fuel Pumps, of which the following is a full, clear, and exact specification.

This invention relates to fuel pumps and 10 particularly to pumps for injecting fuel into the cylinders of high compression internal combustion engines.

One requisite of such pumps is that they start the stream of injected oil very sud- 15 denly and at a definite time in the piston stroke, and that they stop the injection just as suddenly to prevent dribbling the oil on the cylinder walls. The economy of the en- 20 gine depends in great measure on the performance of the pump and its ability to de- 25 liver a definite quantity of oil at a definite time and in a definite way.

An object of this invention is to provide a fuel pump which will meet the above re- 25 quirements.

Another object is to provide a fuel pump which can suddenly start and stop the stream of injected fuel with a means for automatically controlling the injection of the 30 fuel.

These and other objects are accomplished by my invention which comprises a fuel pump having a cylinder, a plunger operable therein, a compression space beneath said 35 plunger and means for maintaining the volume of said compression space substantially constant for a part of the stroke of said plunger and means for suddenly decreasing the volume of said compression space.

Referring now to the drawing, the figure 40 represents a vertical sectional view of my fuel pump. The body of the pump 10 has slidably fitted therein a plunger 11 which normally acts against the compression 45 spring 12. Below the plunger is the usual compression space 13 which communicates with inlet valve 14 and the delivery valve 15, the latter being normally held on its seat by the spring 16. A pipe 17 leads from the 50 main reservoir or source of fuel supply to the pump, and the pipe 18 leads from the delivery valve to the engine cylinder or other part to which fuel is to be supplied. Com- 55 municating with the compression space is a follower 19 which is slidable in the auxiliary

cylinder 20, the follower being normally held upon the stop 21 by a spring 22, which, however, is of such a strength that it will yield to a pressure which is insufficient to force the delivery valve 15 off its seat. A 60 plug 23 which also forms a stop is placed above the follower 19. This plug has a vent 24 to allow of easy access of the air to the top of the follower. It will thus be seen that the movement of the follower may be 65 adjusted by adjusting the heights of the stop 21 and the plug 23.

Another extension of the compression space 13 leads to the by-pass valve 25 which opens communication with an auxiliary res- 70 ervoir 26 which is formed by placing a wall 27 about the upper part of the pump. This reservoir has an overflow pipe 28 which preferably communicates with the main fuel supply tank (not shown). The by-pass 75 valve 25 is normally held on its seat by means of a spring 29 which is relatively stiffer than springs 16 and 22, so that the by-pass will never be forced from its seat by pressure from within the compression 80 space 13.

The plunger 11 is actuated by means of an eccentric 30 and eccentric strap 31 which is pivotally connected at 32 to a rocker arm 33, which in turn is pivotally mounted upon 85 an eccentric 34 which is carried on a bearing 35 on the reservoir wall 27. The opposite end of the rocker arm 33 carries a finger 33^a which engages the underside of a nut 36 on the stem 37 of the by-pass valve 25. The eccentric 34 has an eccentric arm 34^a which is operated by means of a rod 38 from a gov- 90 ernor 39. An operating lever 40 is pivoted at 41 to the reservoir wall to provide a means of operating the plunger 11 by hand. In 95 operation the plunger 11 draws liquid from the reservoir (not shown) through the inlet valve 14. As this valve closes and the plunger descends, the fuel in the compression space 13 forces the follower 19 away from the stop 21 against which it normally rests. As the plunger 11 descends, the follower 19 will be forced up, keeping the compression space 13 constant and the pressure substan- 100 tially so until the upper part of the fol- lower 19 strikes the plug 24, when it will come to a sudden stop, which is the position of the part shown in the figure of the drawing. Moreover, I have preferably shown 105 this action as taking place at the time when 110

the plunger 11 is substantially at the center of its stroke, when it is moving with the greatest rapidity. The effect of suddenly decreasing the compression space, therefore, due to the rapid downward movement of the plunger 11, and the sudden stoppage of the follower 19, is to move the delivery valve 15 from its seat and cause a sudden ejection of fuel through the delivery pipe 18. This gives a very sudden ejection of the fuel, but it is just as necessary that the stoppage of the delivery of the fuel should be just as sudden, and this I accomplish by means of the finger 33^a of the rocker arm 33, which suddenly lifts the by-pass valve 25, forcing the remainder of the fuel due to the stroke of the piston 11 into the reservoir 26. The point at which the by-pass valve will open may be adjusted by means of the nut 36 and the parts which go to make up the governor controlled mechanism.

Fuel pumps of this kind are intended primarily for use on high compression internal combustion engines where the fuel is injected directly into the cylinder. It is very essential that the time during which fuel is injected is very small, but this time can be very accurately predetermined, and this it will readily be seen I have accomplished by my invention.

While I have shown and described but a single embodiment of my invention, it is to be understood that it is capable of modifica-

tion. Changes, therefore, in the construction and arrangement of parts may be made which do not depart from the spirit and scope of the invention as expressed in the following claims:

1. In a fuel pump for internal combustion engines, the combination of a pump cylinder having a compression space, a piston in the cylinder driven from the engine, intake and discharge valves for the cylinder, a follower slidable in a bore in communication with the compression space, adjustable means for limiting the movement of the follower, a by-pass valve, means for opening the by-pass valve, and means controlled by the speed of the engine for determining the point at which the by-pass valve is opened.

2. In a fuel pump for internal combustion engines, the combination of a pump cylinder having a compression space, a piston in the cylinder driven from the engine, intake and discharge valves for the cylinder, a follower slidable in a bore in communication with the compression space, adjustable means for limiting the movement of the follower, a by-pass valve, means for opening the by-pass valve, and means wholly independent of the follower limiting means for determining the point in the stroke of the piston at which the by-pass valve is opened.

In testimony whereof I affix my signature.

THOMAS WILLIAM KINGS.
